FLUID COLLECTOR FOR SMOKING PIPES

Frank O. Field, Oakland, Calif., assignor of one-half to Lucien F. Abadie, Piedmont, Calif.

Application August 22, 1932, Serial No. 629,800

1 Claim. (Cl. 131—12)

This invention is a fluid collector for smoking pipes, and is specially directed to the means for collecting the fluids distilled from tobacco during smoking, and which fluids are normally collected within the stem of the pipe and frequently drawn into the mouth. As these fluids contain injurious substances, being actually poisonous, and in addition thereto, having a very disagreeable taste and odor, it is desirable to provide means whereby these fluids may be prevented from entering the mouth, and readily disposed of.

It is known that pipes have been made with various devices intended to collect these fluids, but in all cases these devices have been impractical, inoperative, or formed in such manner that they were ineffective due to the difficulty in cleaning and removing the fluids. One type is of the curved stem variety in which an auxiliary pocket is formed in which the fluids are to be collected, but this pocket is in such a position that it is almost impossible to clean and soon becomes plugged with gums and fluids which give an extremely bad odor to the pipe and after this condition exists, the cup or chamber is ineffective.

The present invention overcomes all these undesirable features and is readily kept clean, and has no tendency to clog up, and with suitable care, no possibility of drawing any of the fluids into the mouth.

The main object of the invention therefore, is to provide an efficient and practical means of collecting the fluids created by the smoking of tobacco in the pipe.

Another object of the invention is to provide a means as outlined which is readily cleaned and removed, the parts affecting the method being readily accessible and easily cleaned.

A further object of the invention is to provide a replaceable absorbent element for absorbing the liquids, and which element is easily removed and replaced.

Other objects and advantages of the invention will become apparent as the following description is read on the drawing forming a part of this specification and in which similar reference characters are used to designate similar parts throughout the several views, of which:

Fig. 1 is a plan view of my improved pipe.

Fig. 2 is a longitudinal sectional elevation through the invention.

Fig. 3 is an enlarged fragmentary sectional view through the fluid collecting chamber and the absorbing element.

Fig. 4 is an end view of the absorbing element. My invention is applicable to pipes of any stand-

ard form, and is shown in the drawing as consisting of a straight stem pipe having a bowl 10 and a stem 11, these two parts being of the usual construction and provided with the usual smoke passages 12 and 13.

My invention consists of two coaxial stepped counter-bores 14 and 15 formed in the pipe end of the stem 11, and communicating with the smoke passage 13.

An annular recess is formed on the stem end 16 of the bowl or pipe proper, which annular recess fits into the counterbore 14. A ferrule 17 is applied over the pipe end of the stem 11 to cover the locking means, which consists of a pin 18, which is fixed in the end of the pipe as indicated, and which cooperates with an L-shaped slot 19 formed in the pipe end of the stem 11, and through the wall of the large counterbore. A tube 20 is frictionally secured in the passage 12 and projects into the counterbore 14 when the pipe and stem are assembled, the tube being out of contact with the walls of the counterbores.

An absorbent element 21 of cylindrical form fits within the counterbore 14, and has an axial aperture 22 which fits over the tube 20, this element being readily replaceable and adapted to absorb the fluids created by the burning tobacco burnt within the bowl 10.

It will be noted that by the bayonet locking device that the stem is securely and detachably locked to the pipe proper, and that by removing the stem from the pipe, the absorbing element is easily removed and replaced, as it is merely necessary to slide the element off of the tube.

The fluids enter the chamber and are condensed on the walls of the chamber, and flow back into the counterbore 14 where they are collected in the event that the absorbing element 21 is not used, and in the event that this absorbing element is used, the fluids are absorbed by this absorbing element, which element is periodically discarded or washed.

This absorbing element may be formed of any absorbent material such as cotton or linen, or any other material which will effectively absorb the tobacco fluids.

Having described an operative method of collecting the fluids created by the smoking of tobacco within a pipe, it will be understood that variations in the construction and arrangement of parts which are consistent with the appended claim may be resorted to without detracting from the spirit or scope of the invention or sacrificing any of the advantages thereof.

I claim:

A smoking pipe comprising a bowl having a stem-engaging member extending therefrom and having a bore communicating therewith, the 5 outer extremity of said member having an annular projection of reduced diameter, a stem having its bore provided with two contiguous coaxial stepped counterbores, with the larger counterbore located at the bowl end of the stem 10 and closely fitting over the said reduced projection in such manner as to unite the stem

and the stem-engaging portion, a tubular member projecting from the outer end of the bore of said stem-engaging member into the larger counterbore and in axial alinement with the smaller counterbore, and a cylindrical absorbent member enclosing the exposed portion of said tubular member and filling the space between the tubular member and the wall of the larger counterbore.
